J. W. Douglas

Force Pump,

N° 35,059.

Patented Apr. 22, 1862.

UNITED STATES PATENT OFFICE.

JOSEPH W. DOUGLAS, OF MIDDLETOWN, CONNECTICUT, ASSIGNOR TO W.
& B. DOUGLAS, OF SAME PLACE.

IMPROVEMENT IN PUMPS.

Specification forming part of Letters Patent No. 35,059, dated April 22, 1862.

To all whom it may concern:

Be it known that I, JOSEPH W. DOUGLAS, of Middletown, in the county of Middlesex and State of Connecticut, have invented a certain new and useful Improvement in the Construction of Pumps; and I hereby declare that the following is a full and sufficient description thereof, reference being had to the accompanying drawings and references, making part thereof, in which—

Figure 1 is a front elevation of the pump, supposed to be fast to the wall, in which the valve-chest is toward the spectator. Fig. 2 is a side elevation showing the position and location of the valve-chest A' and eduction and induction pipes in place; Fig. 3, a top view of the valves and contiguous openings, the upper half of the valve-chest being removed to show the parts in place; Fig. 4, an inverted view of the upper half of the valve-chest, showing the position of three separate chambers and the eduction-pipe opening; Fig. 5, a view of lower half of the valve-chest after removing the valves, showing the four valve-openings and openings O O'; Fig. 6, a section of valve-chest and induction-pipe, taken through x x of Fig. 3, showing position of the parts on the left side of the valve-chest; Fig. 7, a section through line x² x² of Fig. 3, showing position of parts on right side of the valve-chest; Fig. 8, a section through line x³ x³ of Fig. 6, showing parts seen in front of the pump; Fig. 9, a section through y' y' of Fig. 8, showing the bottom of the chambers O² O² in section, as also the roof k of the same, with the vertical division-walls d d'.

Similar letters and figures in the drawings refer to similar parts, and when right and left sides are named in the description the spectator is supposed to stand in front of the pump with the valve-chest nearest to him, or being toward him, as shown in Fig. 1.

In the drawings, let A represent the pump-barrel; A', the valve-chest, containing the several chambers thereof; A², a side passage for feeding into the lower part of the pump-barrel and communicating with the chamber of valve B.

B is the induction-valve on the left-hand side of the valve-chest; B', the eduction-valve on the left-hand side of the valve-chest; B² B³, openings through the metallic plate imme-

diately under valves B and B', respectively, the valves being removed.

C represents induction-valve on the right side of valve-chest; C', the eduction-valve on the right side of valve-chest.

C² C³ are openings, respectively, through metallic plate under valves C C', the valves being removed.

D is the eduction or discharge pipe; E, the induction or suction pipe; F, the piston; F', the piston-rod; O O', openings in the valve-plate between the induction-valves B and C and communicating between the induction-valves aforesaid and the pump-barrel.

O² O² are cavities or chambers communicating between the openings O O' and the pump-barrel, and O O' and O² O² together constitute the entire passage between the induction-valves and the barrel.

O³, O⁴, and O⁵ constitute the three cup-shaped chambers of the upper half of the valve-chest.

P P represent the bottom plate or floor of chambers O² O², one on each side of the division-wall d.

Letters a a' represent the arrows, showing the direction of the currents entering the pump-barrel from the eduction-pipe E.

a³ a⁴, in red ink, show the direction of the discharge-current from the pump to the eduction-pipe D.

b b' c c' are projecting pins acting as stops for the valve-lids in the upper chambers of the valve-chest, as shown in Figs. 4 and 8.

d d' constitute the division-wall between chambers O² O² and the chambers of induction-valves B and C, while valves B' and C' are operated in a common chamber communicating with the eduction-pipe D.

Letters e e represent a longitudinal partition in the upper half of the valve-chest and extending to the top of the same and separating the eduction-valves C' B' and their communication with the eduction-pipe D from the chambers of the induction-valves C B.

Letters f f' are channels and ridges surrounding the valves and valve-chambers, f representing the channels, and f' the ridges to secure the tightness of the faces of the joint; g g, bolts for fastening the two halves of the valve-chest; g', bolt-holes.

h h represent the leather thickness of the

valve-plate; k , the roof of chamber $O^2 O^2$; xx' $x^2 x^3$, lines for marking the several sectional representations, drawn vertically; $y y' y^2 y^3$, lines showing horizontal sections.

$z z'$ are indications of channels or passages for the currents to enter the pump-barrel, the former entering at the top of the barrel and the latter passing down the side passage, A^2 .

The first feature of the invention respects the location and position of the valve-chest and valves in vertical cylinder pumps.

The second feature of the invention respects the use of a sheet or plate of tinned iron to aid in forming the floor of the horizontal passage $O^2 O^2$, hereinafter to be described.

From the fact that all the parts called the "working parts" of a pump are kept wet, and therefore inclined to rust, and must be frequently required to be inspected and repaired, and its screws, nuts, and bolts be detached, it is very desirable to so construct the machine that there shall be few parts to be detached in getting at all the workings of the valves, and to so arrange these valves that they may be separate from the barrel, and may thus be removed or renewed without disturbing the fastenings and the piston, and, secondly, that they may be exposed to view, if possible, by the opening and closing of a single joint. As ordinarily constructed, pumps required a mechanic to put them together and take them apart, and most of the parts of the machine have to be taken down in order to get at the valves either for inspection or repair.

I have obviated the principal evils complained of by removing the valves and valve-chambers away from the barrel and placing them in an exposed part of the machine entirely accessible by removing three screw-bolts. By this arrangement the four valves $B B' C C'$, as seen in Fig. 3, are placed in one inclosure on one horizontal plane, and every part is accessible and freely exposed to view by the opening of a single joint. The whole plate is covered with a single thickness of leather, except the screw-bolt holes g and the openings $O O'$. The barrel, valve-chest, and contiguous parts are made of iron, the valve-chest cast in two separate parts, bolted together, and then bolted to the barrel or to the side passage, A^2 , of the barrel by the crew g^2 .

The only complicated part of the pump is the construction of the valve-chest and the devious water-channels through it. The valve-plate h constitutes the dividing-line between the upper and lower parts of the valve-chest. The water enters through the induction-pipe E and through the lower half of the valve-chest, thence into the upper half of the valve-chest, thence down through passages $O O'$ and passages $O^2 O^2$ (now to be described) into the barrel, and thence back into the upper chamber of the valve-chest and out through induction-pipe D .

Looking at Fig. 8 of the drawings, which is

a section taken through $x^3 x^3$ of Fig. 6 and $y y^3$ of Fig. 9, I have an end view of a low chamber or cavity, $O^2 O^2$, divided by a partition, d , into which I look from above through the oblong openings $O O'$ in Figs. 3 and 5. In Fig. 9 the roof of said chamber or cavity is removed to show the whole extent of its bottom from the front to the rear thereof, the bottom plate of this cavity being represented by letters $P P$, the letters $O O'$ being used here to show the part of the bottom plate which is directly under the openings $O O'$ in Figs. 3 and 5, and which is seen on looking down through these openings. This bottom plate, $P P$, (seen edgewise in Fig. 8,) as may be inferred by inspection, is a very difficult part to be made of cast metal, and cannot be made in the ordinary way of molding with a core, from the fact that it is an isolated cavity surrounded in part by the cavity of the lower chamber of the valve-chest below and by the roof k , cast of the same metal and as a part of the same operation. This bottom plate, $P P$, required an extra contrivance to insure a sound and perfect casting. To effect this I take an ordinary sheet or plate of roofing-tin cut into the suitable shape, and fix it in its proper place and position, and the metal designed to constitute the floor $P P$ is poured into the mold. The tin which covered the sheet-iron, having a strong affinity for the metal that is poured in, unites firmly to the metallic plate that is underneath it and becomes one firm mass of cast and wrought iron combined. The tin plate acts as a support during the casting, and afterward contributes its firmness and strength to the floor or plate $P P$, aforesaid.

The mechanism to be explained in this apparatus, and already alluded to by the letters and figures used, is chiefly the valve-chest, views showing the upper part of which are seen in Figs. 3, 4, 5, and 9, while sections showing portions of the upper and lower parts together are seen in Figs. 6, 7, and 8. Fig. 6 shows the left-hand side of the valve-chest, while Fig. 7 shows the right side division. Keeping in mind that the spectator is standing in front and looking toward the valve-chest, which is between him and the barrel, valves $B B'$ and opening O are on his left, and valves $C C'$ and opening O' are on his right hand.

The following is the course of the water through the pump: Entering through the induction-pipe E in the direction of the arrows $a a'$, Fig. 8, the water passes up on either side of floor $P P$, through induction-valves $B C$, into the two upper chambers of the valve-chest, over valves $B C$, thence down through openings $O O'$, (see Fig. 3,) into chamber $O^2 O^2$, Fig. 8, following the direction of arrows $a a'$. Thence the currents move horizontally back along the plate $P P$ to the barrel. Current a' , it is to be observed, passes into the top of the barrel, and current a through the side passage, A^2 , at the bottom of the barrel. Current

a' may be traced in Fig. 7, and that of *a* in Fig. 6, the former to the top of the barrel and the latter to the bottom thereof.

Operation. Plunger F being at the bottom of the cylinder, Fig. 6, is drawn upward, and the water communicating with the induction-pipe E follows the movement of the plunger in the direction of the arrows *a*. When the plunger is at the top of the barrel, Fig. 7, and being pushed downward, the water will enter the induction-pipe E and ascend in the direction and follow the course of the arrows *a'*, either of which arrows terminates in the barrel or cylinder. Starting with current *a*, which passes through the left side of the valve-chest, the stream enters E and ascends under and through induction-valve B, Figs. 8 and 6; thence downward through openings O, Fig. 3, into chamber O², Fig. 8; thence along the floor P P, Fig. 9, and down side passage, A², to the bottom of the cylinder. Starting with current *a'* in manner as before, the current enters induction-pipe E, Fig. 7, passes through induction-valve C, thence down O' into chamber O² and along plate P P, Fig. 9, entering the cylinder at top between dotted lines z z. When the current is forced from the bottom of the pump-cylinder, Fig. 6, as when the plunger has been raised to the top, the direction is seen by the lines and arrows *a'* in red ink, passing through induction-valve B', and then out through induction-pipe D. When the current proceeds from the upper end of the cylinder, Fig. 7, it follows the direction of the arrows *a'* in red lines through valve C' and induction-pipe D.

The action of the plunger on the two columns of liquid is obvious. While the plunger is discharging a stream from the lower end of the cylinder it is receiving a charge through or into its upper end, and vice versa.

I would remark that the location and position of the valve-chest and valves are restricted to a particular class of pumps—namely, those having the cylinder in the vertical position, without an opening through the bottom, and also having the valve-chest at the top of the cylinder. These three are indispensable conditions of this improvement. They combine together to form a perpetual fountain of water to keep the piston-packing soft and pliable, so that although the valves may leak, the piston being relatively lower than the valves and covered with water, the functions of its packing remain unimpaired. This combination or relative position of parts, while it protects the piston-packing under all circumstances, at the same time locates the valve-chest in a prominent and easily-accessible part of the machine for inspection and repairs.

Having described the nature of the invention and the several devices used for carrying it into operation, what I claim as my invention, and desire to secure by Letters Patent, is—

1. The combination of a vertical pump-cylinder, the valve-chest in position, as described, and the lower end of the cylinder being made imperforate, substantially in the manner and for the purpose set forth.
2. The use of a tinned-iron plate, P P, to aid in forming the floor of the horizontal passage O² O², extending from the front to the rear of the valve-chest, substantially in the manner and for the purpose described.

JOS. W. DOUGLAS.
